UNITED STATES PATENT OFFICE.

CHARLES A. MILLER, OF STAMFORD, CONNECTICUT, ASSIGNOR TO THE YALE & TOWNE MANUFACTURING COMPANY, OF STAMFORD, CONNECTICUT.

TIME-MOVEMENT.

1,043,531.

Specification of Letters Patent.

Patented Nov. 5, 1912.

Application filed March 26, 1909. Serial No. 486,004.

To all whom it may concern:

Be it known that I, CHARLES A. MILLER, a citizen of the United States, of Stamford, in the county of Fairfield and State of Connecticut, have invented certain new and useful Improvements in Time-Movements; and I do hereby declare the following to be a full, clear, and exact description of the invention, such as will enable others skilled 10 in the art to which it appertains to make and use the same.

My invention relates to time movements, and is designed for use in watches, clocks, time locks, and other similar time movements.

The object of the invention is to prevent the rapid running down of the movement which results when any one of the wheels of a train becomes disengaged from its intermeshing wheel, due to the breaking of one 20 of the staff pivots of the train, and my invention consists in a support for one or more of the staffs intermediate the two pivot bearings of each staff.

For the purpose of illustration I have shown, and will describe my improvement in connection with the time movement of a clock, but I would have it understood that it is equally adapted to watch movements 30 and also to time lock movements, hence I would have it understood that all reference to time movements is intended to comprehend not only clocks but watches, time movement for locks and all other similar time movements.

In the accompanying drawings Figure 1 is a view in front elevation of a time movement embodying my invention. Fig. 2 is a view in side elevation of same, and Fig. 3 40 is a view in section taken on the line *a*, *a* of Fig. 1.

1 and 2 represent respectively the front and rear plates of a time movement, 3 the spring arbor and 4 the escapement wheel, the latter being geared up to the drive pinion on the spring arbor through a train of gears, carried by the staffs 5, 6, 7 and 8, the staff 5 taking its power directly from the pinion on the spring arbor, and the staff 8 50 carrying the escapement wheel 4.

9 is the intermediate plate or bridge provided at its ends with posts by means of which it is secured to one of the plates, in the present instance to plate 1, and provided with openings slightly larger than the

staffs. The posts are of sufficient length to bring the bridge well up, and in close proximity to, the gears so that the latter will be supported in the event of injury to the staffs or pivots thereof at either side of the gears, 60 concentric therewith, through which one or more of the staffs, preferably the faster moving ones of the train pass. I have shown the staffs 6, 7 and 8 passing through openings in the bridge or intermediate plate. 65 The staffs or spindles are provided with pivots or reduced ends of the usual construction, some of which are supported in jewels and others in metal, either steel or brass.

With the time movements now in use, if 70 a pivot breaks, the force of the spring tending to turn the pinion on the damaged staff, moves the latter to one side, thus breaking the train and permitting the spring to unwind rapidly. With my improvement, if a 75 pivot breaks the damaged staff will be supported by the other pivot, and by the bridge or intermediate plate 9, and the force of the spring tending to drive the staff around in the slightly larger hole in the bridge, forces 80 the staff or spindle diagonally against the side of the hole, or into an eccentric position, thus stopping the movement at once. In addition to this function the bridge adds 85 strength to the parts of the movement passing through the bridge, due to the fact that the holes in the latter are so near the size of the staffs or spindles, that the latter may be jarred considerably sidewise, but 90 prevented from actual displacement by contacting with the side walls of the holes through which they pass. The main object however, is to prevent the rapid running down of the movement in the event a pivot should be broken. In a watch, or a high 95 class time piece, if a pivot be broken from one of the spindles or staffs, the rapid unwinding of the spring injures the pinion to such an extent that they are practically worthless for future use, and in large time pieces, where heavier springs are used, the 100 pinions are frequently destroyed. Again in the lock movement, the pivots are sometimes broken by the methods employed by burglars in attempting to open safes and vaults, and thus cause the movement to run down quickly, in which event the safe or vault would be quickly unlocked. By my 105 improvement, the staffs are supported between the pivots, so that if either or both 110

pivots be broken, the staff will simply be thrown from its concentric to an eccentric position and act as a brake.

It is evident that many slight changes might be resorted to in the relative arrangement of parts shown and described without departing from the spirit and scope of my invention hence I would have it understood that I do not wish to confine myself to the exact construction and arrangement of parts shown and described, but,

Having fully described my invention what I claim as new and desire to secure by Letters-Patent, is—

- 15 1. In a time movement the combination of supporting plates, and a gear staff or spindle mounted at its ends in said plates, of a bridge intermediate the plates and embracing the staff or spindle adjacent to the gear on the latter, the hole in the bridge being slightly larger than the diameter of the

staff or spindle whereby upon the displacement of the spindle from its bearing the same is supported in an eccentric position and stops the movement.

2. In a time movement, the combination with front and rear supporting plates and a gear train carried by said plates, of a bridge intermediate the plates and having holes for the passage of two or more of the 30 staffs of the gear train, the said holes being slightly larger than the staffs whereby upon the displacement of a staff from its bearing, the same is supported in an eccentric position and stops the movement.

In testimony whereof, I have signed this specification in the presence of two subscribing witnesses.

CHAS. A. MILLER.
